UNITED STATES PATENT OFFICE.

CLARENCE C. GRAHAM, OF SAN FRANCISCO, CALIFORNIA.

DESIGN FOR A COMBINED CIGARETTE HOLDER AND DISPENSER.

Application filed April 3, 1929. Serial No. 30,744. Term of patent 7 years.

To all whom it may concern:

Be it known that I, CLARENCE C. GRAHAM, a citizen of the United States, residing at the city and county of San Francisco, State of California, have invented a new, original, and ornamental Design for a Combined Cigarette Holder and Dispenser, of which the following is a specification, reference being had to the accompanying drawings, forming a part thereof.

The drawing is a perspective view of a combined cigarette holder and dispenser.

I claim:

The ornamental design for a combined cigarette holder and dispenser, as shown.

CLARENCE C. GRAHAM.
